US0D1027884S

(12) **United States Design Patent** (10) **Patent No.:** **US D1,027,884 S**
(45) **Date of Patent:** **** May 21, 2024**

(54) **LED DISPLAY**

(71) Applicant: **Yancheng Yiwei Photoelectric Technology Co., Ltd.**, Yancheng (CN)

(72) Inventor: **Bijian Lin**, Yancheng (CN)

(73) Assignee: **Yancheng Yiwei Photoelectric Technology Co., Ltd.**, Yancheng (CN)

(**) Term: **15 Years**

(21) Appl. No.: **29/854,025**

(22) Filed: **Sep. 21, 2022**

(51) LOC (14) Cl. **14-03**

(52) U.S. Cl.

USPC **D14/126**

(58) **Field of Classification Search**

(57) **CLAIM**

The ornamental design for a LED display, as shown and described.

DESCRIPTION

FIG. 1 is a front, right and bottom perspective view of a LED display, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1; and,

FIG. 13 is an enlarged view of portion 13 shown in FIG. 1.

The dot-dash broken lines depict the boundaries of the enlargements that form no part of the claimed design.

1 Claim, 13 Drawing Sheets
